[57] CLAIM

The ornamental design for a folded lid for a bin, as shown and described.

DESCRIPTION

FIG. 1 is a top and front perspective view of a folded lid for a bin showing my new design; the broken lines are for illustrative purposes only and form no part of the claimed design;

FIG. 2 is a bottom plan view thereof;

FIG. 3 is a right side elevation view thereof;

FIG. 4 is a front elevation view thereof;

FIG. 5 is a left side elevation view thereof;

FIG. 6 is a rear elevation view thereof;

FIG. 7 is a cross sectional view thereof taken along the line 7—7 of FIG. 2; and,

FIG. 8 is a cross sectional view thereof taken along the line 8—8 of FIG. 2.

FIG. 1

FIG. 3

FIG. 6
